HEAT EXCHANGER

Harold M. Graham, Bronxville, and Frederick D. Berkeley, Chappaqua, N. Y., assignors to The Lummus Company, New York, N. Y., a corporation of Delaware

Application October 31, 1941, Serial No. 417,290

2 Claims. (Cl. 257—246)

This invention relates to heat exchangers and more particularly to that type of heat exchanger known as a double pipe heat exchanger or cooler, wherein a hot fluid and a cold fluid are passed in indirect heat exchange relation through two relatively concentric tubes.

It is known that double pipe heat exchangers or coolers have particular advantage where high heat transfer efficiency is required and especially where the volumes of the heat-exchanging fluids are small and their temperature difference is relatively great. It is also known that the use of a finned or extended surface tube in such a heat exchanger materially increases the heat exchange efficiency where the fluids undergoing heat exchange have relatively different heat transfer characteristics. For example, in the transfer of heat energy from a gas or a vapor such as condensing steam to a liquid such as oil, a substantial increase in heat transfer can be obtained by the use of a finned tube. It will be apparent, however, that there is a limit to the extended surface possible for any tube.

The principal object of our invention is to increase the heat exchange efficiency of a finned tube double pipe heat exchanger whereby a greater heat transfer rate can be obtained per unit tube length.

Another object of our invention is to provide a standardized finned tube double pipe heat exchanger, in which the outer tube may be a standard size pipe and the fin on the inner tube is adapted to closely fit the outer tube and in which the ends of the tubes are provided with simple caps for headers.

A more specific object of our invention is to provide a helically finned inner tube for a double pipe heat exchanger, the fin of which engages in a helically threaded recess in the outer tube in such a manner that the inner tube may be screwed into position in the outer tube to present a substantially liquid-tight construction that prevents the by-passing of the external fluid between its inlet and outlet.

Further objects and advantages of our invention will appear from the following description of preferred forms of embodiment thereof taken in connection with the attached drawing, in which:

Fig. 1 is a substantially central vertical section with parts in elevation of a double pipe heat exchanger;

Fig. 2 is a view similar to Fig. 1 showing a slightly modified form of construction;

Fig. 3 is a vertical section with parts in eleva-

tion of a still further modified form of double pipe heat exchanger; and

Fig. 4 is a vertical transverse section taken substantially along the line 4—4 of Fig. 3.

5 We have shown in Fig. 1 a double pipe heat exchanger or cooler unit that includes an outer preferably cylindrical tubular member generally indicated at 10, which desirably has a uniform diameter and wall thickness throughout and which may be a standard piece of pipe cut to a predetermined length. According to our invention, the internal surface of this outer tube is provided with a helical channel or recess 12 extending substantially throughout the length of the tube. This channel has a depth and a width that adapt it to receive the edge portion of the helical fin 14 formed on the external surface of the inner tubular member 16.

The inner tubular member 16 may be conveniently made of relatively thin metal, and the helical fin 14 may be formed thereon by any suitable process. Preferably, however, the construction is such that fin 14 is integral with tube 16. The fin may also desirably have a triangular cross section as shown; for in this manner a more efficient conduction of heat through the extended surface is assured. Fin 14 is continuous throughout its entire length but does not extend to the ends of the inner tube 16. The terminal portions of the external surface of tube 16 are thus free of a finned surface for a purpose more fully explained hereinafter.

As already indicated, in this form of embodiment the external diameter of fin 14 is slightly 35 greater than the internal diameter of the outer tube 10. It will be apparent that the pitch of the channel 12 and the pitch of the fin 14 are of necessity the same. Accordingly, when the unit is assembled, helical chamber 17 is formed by the 40 fin and the external surface of the inner tube and the internal surface of the outer tube. A long continuous path of flow is thus provided for the external fluid, which path may be many times the length of the path of flow of the internal fluid.

45 This double pipe unit may be conveniently assembled by inserting the inner tubular member 16 into the outer tubular member 10 so that the helical fin 14 engages the helical channel 12 and then rotating tube 16 until it is in the desired position. Each end 18 of the inner tubular member, being free of fin 14, may then be suitably expanded into contact with the internal surface of the outer tubular member 10 to form a relatively tight joint to prevent leakage of the external fluid. For this purpose the length of both

of the tubular members is desirably made the same. Expansion of ends 18 of the inner tube 16 also serves to lock the inner tube in the desired position with respect to the outer tube 10.

Helical chamber 17 is made fluid-tight by reason of the engagement of fin 14 in the helical channel 12. By-passing of the external fluid between inlet nozzle 20 and outlet nozzle 21 is substantially and, in most cases, entirely prevented since there is little, if any, possibility for such fluid to flow across the outer edge of fin 14. Accordingly, all of the external fluid must follow the helical path defined by chamber 17 with its relatively great heat transfer surface.

Suitable headers such as internally screw-threaded caps 22 and 23 are adapted to be secured to the ends of external tubular member 10, which is suitably threaded as shown. These caps are provided with nozzles 24 and 25, respectively, for the introduction of the internal fluid into inner tube 16 and the discharge of such fluid therefrom. By virtue of the expanded terminal portions of the inner tubular member 16, the two heat exchanging fluids can be maintained in indirect contact. The two fluids may flow in counter-current relation as shown or in concurrent relation if desired.

This form of embodiment of our invention may be readily assembled for use and quickly disassembled for inspection, cleaning, and the like. It has a high heat transfer efficiency, *inter alia*, because of the prevention of by-passing of the external fluid across the fin 14 and because of the increased turbulence of flow of the external fluid. A plurality of double pipe units of this type may be combined into one larger unit where such an assembly is required or practicable as when a substantial amount of heating or cooling must be done. It will be appreciated that a single unit may also be made of sufficient length to provide single-pass operation. The apparatus is particularly well adapted for the heating of fuel oil or the like as by steam.

A slightly modified form of embodiment of our invention, which is somewhat cheaper to construct than that shown in Fig. 1, is shown in Fig. 2. In this case the outer tubular member 10a is similarly provided with inlet and outlet nozzles 20 and 21 and is also similarly provided with screw-threaded caps 22 and 23 for the passage of the external fluid through the inner tubular member 16a as by nozzles 24 and 25. Inner tubular member 16a is likewise similarly provided with a continuous helical fin indicated at 14a. In this embodiment, however, the external diameter of fin 14a is substantially the same as the internal diameter of the outer tubular member 10a. The relation between the two diameters is preferably such that fin 14a is in contact with the internal surface of outer tubular member 10a whereby substantially no by-passing of the external fluid across fin 14a occurs as such fluid flows through helical path 11a. The elimination of the helical channel or recess in the outer tubular member 10a permits the direct insertion and removal of the inner tubular member 16a.

In this construction each end 18a of the inner tubular member 16a may be sealed with respect to the outer tubular member 10a by expansion of each terminal portion of the inner tubular member to force it into a circular groove 10b located in the corresponding terminal portion of the internal surface of the outer tubular member in accordance with the customary manner of ex-

panding tubes in tube sheets in condensers and the like. This particular construction in some cases may be more effective than the mere expansion as shown in Fig. 1. Especially where the heat exchanging fluids are such that mutual contamination should be avoided, the method of expansion shown in Fig. 2 is to be preferred.

A still further modification of our invention is shown in Figs. 3 and 4. In this type of double pipe heat exchanger, we have provided a similar form of outer tubular member 30 having the inlet nozzle 20. The inner tubular member 32 is provided with a fin 34, the external diameter of which is substantially the same as the internal diameter of the outer tubular member 30 as was the case with the unit shown in Fig. 2. Each end 35 of the inner tubular member 32 may be expanded in the manner as shown in Fig. 1 to make a tight joint with the outer tubular member 30. A screw-threaded cap (not shown) may also be provided for each end of the outer tubular mem-

ber. It will be noted that, in this construction, helical fin 34 is discontinuous and that it is divided into a plurality of discontinuous sections such as 34a, 34b, 34c, and 34d. These discontinuous sections are preferably alternately arranged so that the helical motion imparted to the flow of the external fluid by the helical fin will not be too greatly affected. In the particular construction shown the discontinuous sections are alternately and diametrically opposed. It will be understood, however, that the arrangement of these discontinuous sections may be any desired such as the positioning of the discontinuous portion of a subsequent section at an angle of 90° from the discontinuous portion of the preceding section and that the discontinuous portions of all the sections may be in a straight line if desired.

The advantage of such construction is that a greater amount of liquid can be passed through the helical chamber 40 between the fin and the two tubular members while the features of the heat exchange units shown in Figs. 1 and 2 are retained to a substantial extent. The helical shape of the fin gives the external fluid a substantially helical path of flow, but at the same time its discontinuous construction permits a portion of such fluid to flow in a straight path. Accordingly, an average rotating velocity is obtained while the pressure drop which the external fluid suffers during its flow is not so great because of the partial by-passing thereof through each discontinuous section of fin 34. Since the discontinuous portions of the several discontinuous sections of fin 34 may be alternately arranged in any particular manner along the length of the inner tubular element, there is an alternately longitudinal as well as a helical motion imparted to the external fluid in its extended path of flow. A relatively high heat transfer efficiency is maintained because of the thorough mixing accomplished and the improved surface contact obtained. It will be apparent that this discontinuous feature may be applied to a double pipe heat exchanger of the type shown in Fig. 1.

For economy of space, lightness of weight, low cost, and high efficiency, an exchanger of this character is especially satisfactory; and material benefits result from its use on installations within its effective range. It will be appreciated that the factors of length and of duplication of a unit are primarily dependent upon the desired or requisite amount of heat transfer and the nature of the heat transfer mediums. It will

also be appreciated that the helical fin constructions shown in Figs. 1, 2, and 3 may be used in a double pipe heat exchanger in which the terminal portions of the inner tubular member are secured in relation to the outer tubular member in any other suitable manner.

While we have shown and described preferred forms of embodiment of our invention, we are aware that other modifications may be made thereto; and we, therefore, desire a broad interpretation of our invention within the scope and spirit of the description herein and of the claims appended hereinafter.

We claim:

1. A double-pipe heat exchanger comprising an outer tube of substantially uniform internal diameter and having a fluid inlet and a fluid outlet spaced therealong, an inner tube having its terminal portions expanded into sealing contact with the internal surface of the outer tube to form fluid-tight joints therewith and to form an outwardly flaring inlet at one end of said inner tube and an outwardly flaring outlet at the other end thereof, means for passing a fluid through the inner tube, and a helical fin on the external surface of the inner tube and terminating short of the ends of the latter, a number of suc-

cessive convolutions of said fin having gaps in alignment longitudinally of said tubes, and a following number of successive convolutions of the fin having uninterrupted portions in opposition to said gaps and also having gaps spaced around the inner tube out of alignment with said first gaps, for the purpose set forth.

2. A double-pipe heat exchanger comprising an outer tube, an inner tube extending longitudinally within said outer tube, means for passing a fluid through said inner tube, means for passing a fluid through the space between said tubes for indirect heat exchange with the fluid in the inner tube, and a helical fin within the space between said tubes and extending therealong and around the exterior of the inner tube, a number of successive convolutions of said fin being formed to provide openings therethrough at points in alignment along the tubes and a following number of successive convolutions of said fin having uninterrupted portions in opposition to said openings and being formed to provide openings therethrough spaced around the inner tube out of alignment with said first openings, for the purpose set forth.
